UNITED STATES PATENT OFFICE.

JOHN BRADFORD, OF CHICAGO, ILLINOIS, ASSIGNOR TO HIMSELF AND
MICHAEL W. HANLEY, OF SAME PLACE.

DEVICE FOR OPERATING POWER GRAIN-SHOVELS.

SPECIFICATION forming part of Letters Patent No. 317,083, dated May 5, 1885.

Application filed January 12, 1885. (No model.)

To all whom it may concern:

Be it known that I, JOHN BRADFORD, residing at Chicago, in the county of Cook and State of Illinois, and a citizen of the United States, have invented certain new and useful Improvements in Devices for Operating Power Grain-Shovels, of which the following is a full description, reference being had to the accompanying drawings, in which—

10 Figure 1 is a top or plan view of the devices pertaining to the invention; Fig. 2, a side elevation of the same; Fig. 3, a detail showing the rope-hook on the lower end of the rod through which the lever-latch is operated.

15 It is customary to operate power grain-shovels by the use of a winding-drum and a rope, the drum being mounted loosely on a constantly-rotating shaft, on which shaft is a sliding clutch by which the drum can be made to rotate with the shaft, or independent thereof, to wind the rope up or permit the rope to be unwound; and the object of this invention is to automatically throw the clutch into and out of gear as required to wind up the rope 20 and draw the shovels forward, or to allow the drum to run free for the rope to unwind and draw the shovels back; and its nature consists in the several devices and combinations of devices, hereinafter described, and pointed out 25 in the claims, as new for attaining the object sought.

In the drawings, A represents the shaft, driven by an engine or other motive power, as is usual in grain-elevators.

30 B is a drum loosely mounted on the shaft A.

C is a rope winding on and unwinding from the drum B, the end being secured in any firm manner to the drum, which rope runs out from the drum, passing around the guide-pulleys 35 C' C'', and having attached to its end the grain-shovel which is to be operated.

D is a second drum, of somewhat less diameter than the drum B, as shown, and connected with the drum B so as to rotate therewith.

40 E is a chain, one end of which is secured in any firm manner to the drum D, so that the chain can wind on or unwind from the drum.

F is the long arm of a bell-crank lever, to which, at a, is secured the end of the chain E. 45 This lever is pivoted at b to the supporting frame-work, and its short arm F' is forked to

engage with the sliding portion of the clutch which operates the drum B.

G is the stationary and G' the sliding portion of the clutch, the part G being formed with or suitably secured to the end face of the drum B, and the sliding part being connected with the shaft A by a feather or otherwise, so that it can move forward and back on the shaft, and at the same time rotate with the shaft, 55 and, as shown, this sliding part G' is provided with a groove to receive the fork of the arm F', so that as the bell-crank lever is turned it will act to engage the clutch or disengage it.

H is a latch pivoted at c to a bracket or support on the frame-work in such relation to the arm F as to have the free end of the latch H drop thereover and hold the arm in position to keep the clutch disengaged, as shown in Fig. 1.

I is the long arm and I' the short arm of a lever pivoted in the upper end of a standard or post, I'', extending up from the frame-work, and to the short arm I' of this lever is connected by a link or rod, d, the free end of the latch H, so that as the long arm of the lever is thrown down the latch will be raised to allow the arm F of the lever to pass thereunder.

J is a link or rod connected at one end to 80 the long arm I of the latch-lever.

K is a bar or lever centrally pivoted to the end of the rod or link J, and, as shown, pins e are provided to form stops to limit the raising of the bar K at each end.

85 L are guides, in which the ends of the bar K move and by which the bar is held so as to operate in a direct line. As shown, these guides are fastened to a board or support, L', and the pins e are also located in this board 90 or support L'.

M are rods, one for each end of the bar K, and each having at its free end a hook, f, to support the winding rope C when the rope is thrown thereon after the shovel has been 95 drawn back.

N is a chain, one end of which is secured to the end of the arm F, and the other end has attached thereto a weight, N'', the chain passing over a roller or pulley, N', mounted on a 100 box, N'', in which box the weight N'' is located, the box being attached to the framing.

O are side pieces, and O' end pieces supporting the shaft, drum, and other devices, the shaft being mounted in suitable boxes on the end pieces, O'.

5 P is the chute, up which the grain is to be carried by the buckets, as usual, the buckets operating in the usual manner, and being, therefore, not shown.

Q is a cross-piece supporting the pulleys 10 C', which cross-piece, as well as the cross-piece L', may be attached to the chute P, or supported in some other suitable manner to bring the devices supported by such cross-pieces in proper position for use.

15 The operation is as follows: As shown in Fig. 1, the parts are in position to unwind the rope to carry the shovel back into the car to be loaded and be advanced to discharge the grain at a point where it can be taken by the 20 elevator-buckets and delivered into the bin or bins, in which position the clutch is disengaged, the part G' being carried back by the arm F', and the arm F being locked and held against horizontal swing by the latch H, 25 and the rope C is clear of the hook f. When the shovel has been carried back the distance required, the rope C is allowed to drop onto the hook f, pulling down the rod M and with it the end of the arm K, to which the rod is 30 attached, and such downward movement of the arm K draws down the link J and the long arm of the lever I, raising the short arm I' and the free end of the latch H through the connection d, and as the free end of the latch 35 is raised the arm F is released from its engagement therewith and the weight N" acts and draws such arm outward, throwing inward the arm F', carrying the clutch G' into engagement with the clutch part G, and connecting the drum B with the shaft A, so that the rotation of the shaft will rotate the drum, 40 winding the rope C up thereon and advancing the shovel attached to the rope, and this connection of the drum with the shaft also 45 rotates the drum D, unwinding the chain E therefrom, and winding it thereon again, and as the chain E winds onto the drum it will draw the arm F inward, throwing outward the arm F', and this movement 50 will occur at the time that the shovel has reached the discharge-point or limit of its advance movement, and as this point is reached the arm F has been drawn into the required point for the latch H to drop thereover, holding 55 the arm against outward movement and holding the clutch disengaged, and such locking of the arm and disengagement of the clutch releases the drum B from the shaft A, so that it can be revolved in a reverse direction by 60 the operator drawing down the shovel and unwinding the rope C therefrom to carry back the grain-shovel, and in such operation of unwinding the rope from the drum the chain will also be unwound and rewound in the 65 opposite direction to that in which it was oper-

ated by the advance of the shovel without affecting the lever F, and when the shovel has been drawn back the chain E is unwound from the drum, so that as the latch H is released the weight N" is free to act and draw the lever-arm F outward to throw the clutch into use.

The devices are very simple, and can be applied to the winding-drums and clothes now in use, and in use the devices work automatically, both in throwing the clutch into engagement and disengaging the clutch from the drum, the dropping of the shovel-rope onto the hook f releasing the holding devices for the lever F F', allowing the lever to act and 70 throw the clutch into engagement, and the winding of the chain onto the drum D operating to draw the end of the arm F inward to release the clutch and allow the drum to run free.

80 A rod, M, is provided for each end of the balance-bar K to enable the rope C to be carried either to one side or the other, as required, for the operation of the shovel, and be dropped to engage a rod, M, and release the 85 latch H.

The stops e each form a fulcrum for the bar K, according as one end or the other of such bar is depressed by the weight of the rope on the rod M, the stop acting to prevent the end 95 of the bar which goes up from traveling too far in an upward direction, and also forming the point against which the bar bears.

The latch H, operated automatically from the shovel-rope, acts instantaneously to release the lever-arm F and throw the clutch into engagement as the rope C is dropped onto the rod M, by which arrangement a quick action in throwing the clutch into engagement is had, and the operator has no trouble 100 in this regard, as the simple act of dropping the shovel-rope insures the disengagement of the lever-arm and the engagement of the clutch.

105 What I claim as new, and desire to secure 110 by Letters Patent, is—

1. The combination, with the shaft A, winding-drum B, and clutch G G', lever F F', drum D, chain E, and latch H, of the lever I I' and balance-bar K, automatically operated from 115 the shovel-rope to allow the clutch to be engaged, substantially as and for the purpose specified.

2. The combination, with the shaft A, drum B, rope C, lever F F', clutch G G', and latch 120 H, of the lever I I', balance-bar K, draw-rod M, and weight N", for automatically raising the latch and throwing the arm F out to engage the clutch, substantially as and for the purpose specified.

JOHN BRADFORD.
